[57] CLAIM

The ornamental design for a combined scraper and garbage disposer aid for sinks, as shown and described.

DESCRIPTION

FIG. 1 is a top perspective view of a combined scraper and garbage disposer aid for sinks showing our new design;

FIG. 2 is a top plan view of FIG. 1;

FIG. 3 is a front elevational view of the scraper and garbage disposer aid for sinks of FIG. 1;

FIG. 4 is a side elevational view of FIG. 1 of which the other side elevational view is a mirror image;

FIG. 5 is a rear elevational view of FIG. 1; and,

FIG. 6 is a bottom plan view of FIG. 1.
